US0D1033445S

(12) **United States Design Patent** (10) **Patent No.:** **US D1,033,445 S**
(45) **Date of Patent:** **** Jul. 2, 2024**

(54) **DISPLAY SCREEN OR PORTION THEREOF
WITH GRAPHICAL USER INTERFACE**

9/451; G06F 40/103; G06F 40/106; G06F 40/189; G06F 40/191; G09G 5/14; H05B 47/19

(71) **Applicant:** **Lutron Technology Company LLC,**
Coopersburg, PA (US)

See application file for complete search history.

(72) **Inventors:** **Erica L. Clymer**, Northampton, PA (US); **Praneetha Jonnala**, Allentown, PA (US); **James Mathias Weber**, Allentown, PA (US); **Jennifer Wong**, Breinigsville, PA (US)

(73) **Assignee:** **Lutron Technology Company LLC,**
Coopersburg, PA (US)

(**) **Term:** **15 Years**

(21) **Appl. No.:** **29/835,479**

(22) **Filed:** **Apr. 19, 2022**

Related U.S. Application Data

(63) Continuation of application No. 29/768,074, filed on Jan. 27, 2021, now Pat. No. Des. 953,364, which is a continuation of application No. 29/732,187, filed on Apr. 22, 2020, now Pat. No. Des. 914,740, which is a continuation of application No. 29/689,882, filed on May 2, 2019, now Pat. No. Des. 883,321, which is a continuation of application No. 29/621,353, filed on Oct. 6, 2017, now Pat. No. Des. 848,471, which is a continuation of application No. 29/575,797, filed on Aug. 29, 2016, now Pat. No. Des. 802,622.

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design. The text illustrated in dashed broken lines forms no part of the claimed design.

1 Claim, 1 Drawing Sheet
